DESIGN FOR A FIGURINE OR SIMILAR ARTICLE

John Herbst, New York, N. Y.

Application July 12, 1941, Serial No. 102,065

Term of patent 3½ years

To all whom it may concern:

Be it known that I, John Herbst, a citizen of the United States, residing in New York city, in the county of Bronx and State of New York, have invented a new, original, and ornamental Design for a Figurine or Similar Article, of which the following is a specification, reference being had to the accompanying drawing, forming part thereof.

Fig. 1 is a side view of a figurine or similar article showing my new design.

Fig. 2 is a perspective view of the other side of Fig. 1, and

Fig. 3 is the rear view thereof.

I claim:

The ornamental design for a figurine or similar article, substantially as shown.

JOHN HERBST.
